S. D. BUTTERWORTH

DOORLOCK

Filed May 28, 1923

Inventor
Samuel D. Butterworth

By Stuart C. Barnes
Attorney

UNITED STATES PATENT OFFICE.

SAMUEL D. BUTTERWORTH, OF LANSING, MICHIGAN.

DOORLOCK.

Application filed May 28, 1923. Serial No. 641,831.

To all whom it may concern:

Be it known that SAMUEL D. BUTTERWORTH, citizen of the United States, residing at Lansing, in the county of Ingham and State of Michigan, has invented certain new and useful Improvements in Doorlocks, of which the following is a specification.

This invention relates to door locks and more particularly to that class of locks provided with a roll striker.

One difficulty with the roll striker locks has been that the door may be pushed open when an excessive force is applied to the door. When the carpenter installs a lock within the door, he mortises out a hole in which the lock casing is adapted to fit. As a general rule, he makes his hole of a greater depth than is necessary and, therefore, the back of the casing does not bear on a solid support. When the roll striker is dogged so as to lock the roll within the striker plate, it will, under ordinary conditions, lock the door, but if one puts his shoulder to the door and exerts an extraordinary force against the same, he will force the roller out of the striker plate by causing the face plate of the lock casing to bend inwardly since there is no solid support behind the casing to prevent this inward distortion under the extraordinary forces exerted by wedging the roller against the inclined wall of the keeper plate.

One of the objects of this invention is to overcome this difficulty by providing a deadlocking bolt which has two functions; to wit, the deadlocking of the door and the dogging of the roll striker. By utilizing the deadlocking bolt in this manner, I convert the entire breadth of the latching means, which includes the roll striker and bolt into a deadlocking bolt. The addition of the deadlocking bolt relieves the chance of any force being exerted on the roll striker, which eliminates any chance of the force exerted on the door causing the roller to ride out of the recess in the striker plate and produce a wedging action, causing the face plate of the casing to become distorted.

In the drawings:

Fig. 1 is an elevation of the lock with the casing cover removed, showing the bolt projected.

Fig. 2 is a similar view showing the bolt retracted.

Fig. 3 is a section of the line 3—3 of Fig. 1.

Fig. 4 is a detail in perspective of the bolt.

Fig. 5 is a detail in perspective of the bolt dogging member.

Fig. 6 is a detail in elevation of the key used.

A door *a* is provided with the usual mortised hole *b* in which a lock casing *c* is adapted to be fitted. The lock casing is provided with the usual face plate *d*, which is secured by screws to the door in the usual manner.

Slidable within the lock casing is a pair of separate roll-bearing members *e*, yieldably forced outwardly by the spring *f*. A pin *g* is carried by the roll-bearing members, and intermediate of the bearing members are a pair of rubber rolls *h*, which are rotatably mounted on said pin. These rolls are of such a length as to leave a space in-between. A bolt *i* is slidably supported within the casing and is adapted to project in the space left between the rolls. The outer end of the bolt is provided with a slot *j* which is adapted to span the pin *g* when the bolt is projected out of the casing, the bolt engaging the pin for the purpose of dogging the rolls. The opposite end of the bolt is provided with a V notch *k*, the side walls of which are adapted to be engaged by the key *l* whereby the bolt may be moved to a locked or unlocked position. The back of the bolt is provided with a lug *m*, which is adapted to be engaged by a downturned ear *n* of the tumbler *o*. This tumbler is provided with a leaf spring *p* which bears against a support carried by the casing, which forces the said tumbler against the bolt.

As shown in Fig. 1, the downturned ear *n* is engaged behind the lug *m*. In Fig. 2, the bolt has been retracted and the ear of the tumbler is located in front of the lug *m*, which will hold the same in a retracted position. When the key is turned in the lock, the striking edge of the key designated *r* will first engage the edge *x* of the tumbler to dis-engage the ear *n* from the lug *m* and further movement of the key will engage the side wall of the V notch *k* in the bolt to actuate the same, and the tumbler is allowed to spring back, so as to engage the other side of the lug *m* when the key is removed to hold the bolt.

A striker plate *s* is provided with a recess *t*, the central portion of this recess adapted to receive the deadlocking bolt while the

adjacent portions of the recess have inclined walls *u* on which the rolls ride upon the opening of the door. In ordinary roll locks when the roll is dogged, an excessive force applied to the door will force the roll against the incline and wedge the same. This wedging action will force the roll inwardly against the resistance of its dogging means, and the construction of the casing is such that it is not strong enough to withstand the forces, but will buckle and give away under the strain.

Obviously when the bolt is projected from the casing it is held in this projected position by the tumbler *o* and the door is securely locked, the deadlocking bolt thereby relieves the strain from the rolls when any force is applied to the door and therefore does not allow any wedging action of the roll and the incline of the striker plate which tends to bend or break the other parts of the lock, when any extraordinary force is applied to the door.

What I claim is:

1. A door lock, having in combination, a casing, a roll striker slidably supported therein, means for yieldingly forcing the same outwardly, a striker plate provided with a recess having inclined walls for the roll to ride upon, and a deadlocking bolt slidably supported within the casing intermediate the ends of the roll striker, the said bolt arranged to straddle the roll to also dog the same.

2. A door lock, having in combination, a

casing, a two-part roll striker slidably supported therein, the said parts spaced from each other, means for yieldingly forcing the same outwardly, a striker plate provided with a recess having inclined walls for the rolls to ride upon, and a deadlocking bolt slidably supported within the said casing and adapted to slide between said rolls and provided with means for straddling the said two-part roll striker to also dog the same. 45

3. A door lock, having in combination, a casing, a roll striker comprising a pair of rolls and a pin for supporting the rolls, said rolls spaced from each other, a striker plate provided with a recess having inclined walls 50 for the rolls to ride upon, and a deadlocking bolt slidably supported within said casing provided with a slot in the end thereof, said bolt adapted to engage with the pin supporting the rolls when the same is projected out from the casing for the purpose of dogging the rolls.

4. A door lock, having in combination, a casing, a roll striker comprising a pair of spaced rolls and a pin for supporting the 60 rolls, means for yieldingly forcing the same outwardly, a striker plate provided with a recess having inclined walls for the rolls to ride upon, and a deadlocking bolt slidably supported within said casing and arranged 65 to engage with the pin for the purpose of dogging the rolls.

In testimony whereof he has affixed his signature.

SAMUEL D. BUTTERWORTH.
